INVENTOR

BY *R. Cowright.*

ATTY.

UNITED STATES PATENT OFFICE.

HORACE D. CARTER, OF MULTNOMAH, OREGON.

SWIMMING POOL.

1,403,009.

Specification of Letters Patent. Patented Jan. 10, 1922.

Application filed October 4, 1920. Serial No. 414,636.

To all whom it may concern:

Be it known that I, HORACE D. CARTER, a citizen of the United States, residing at Multnomah, in the county of Multnomah and State of Oregon, have invented a new and useful Improvement in Swimming Pools, of which the following is a specification, reference being had to the accompanying drawings.

10 My invention relates to devices as a class, wherein water is confined for instruction or pleasure purposes, commonly called swimming pools or tanks.

15 My object is to provide a device of this character wherein a tank or container is provided with mechanism to force streams of water upwardly from the bottom thereof to agitate and allow buoyancy of the water therein at its surface, also to allow a continuous changing of water in said tank. These objects, as well as other advantages, I attain by the construction, combination and arrangement of parts illustrated in the accompanying drawings which form a part 20 hereof.

Fig. 1 is a side elevation of the device, partly in section on the line 1—1 in Fig. 2.

Fig. 2 is a plan view with parts of pipe connections omitted.

30 Like characters refer to like parts in the views.

In the form illustrated, a primary water tight tank 3 is provided. Within said tank a secondary tank 4, of desired lesser dimensions and height is placed upon a series of supports 5. The tank 4 has spilling rims 6 about its upper edges and a discharge port 7 in the bottom. In one end of the tank 3, near its bottom, a T-pipe 8 is placed. Its 35 shorter arm extends without the tank, its longer arm transversely within the tank. A series of pipes 8^a extend from the longer arm of the T-pipe longitudinally within the tank 3 and below the tank 4, their opposing 40 ends being closed. A series of short branch pipes or jets 9 extend upwardly from the pipes 8^a and through the bottom of the tank 4 into which the jets 9 open. Without the tank 3 the shorter arm of the T-pipe 8 has 45 a two-way valve 10. From this valve, one pipe 11 extends to a desired outer source of water supply and another pipe 12 extends to a pump 13. A feed pipe 14 extends from the pump to a two-way valve 15. From 50 this valve one feed pipe 16 extends to a suitable outer source of water supply and another pipe 17 extends to a third two-way valve 18. From this valve one pipe 19 extends into the tank 3 near its bottom and another pipe 20 extends to a suitable location for discharge of water. 60

It will now be seen that, by means of the pipe system illustrated, water from the primary tank 3 may be pumped therefrom and forced, through the pipe series 8^a and 65 the jets therein, upwardly through the body of water in the secondary tank 4 toward the surface of said water, which then falls over the spillway at the ends or sides into the primary tank, and is again pumped through 70 the same circuit. In this operation, the valve 10 is closed to the pipe 11 and opened to the pipe 12, the second valve 15 is closed to the pipe 16 and opened to the pipe 17 and the third valve 18 is opened to the pipe 17 75 and closed to pipe 20. It is understood that in this operation the tanks are first supplied with water in a desired quantity to retain the secondary tank filled and enough in the primary tank to insure the same supply in 80 the secondary tank as it is spilled over during the pumping. It will further be seen that by a proper setting of the valves, water from an outside source may be pumped through the pipe 16, and, after passing 85 through the tanks as described, discharged through the pipe 20. It will again be apparent that by a different setting of the valves at each end, water under pressure from a desired source, such as the main of 90 a water system, may be forced through the pipe 11 and the tanks in the same way and discharged through the pipe 20. The first method is intended for the use of the same water with which the tanks are first supplied, when it is necessary to economize in 95 the water supply. In this case filtering means may be installed at some convenient position in the pipe circuit. The second method is for use where the supply of water 100 is unlimited, for example, when the tanks are placed in a stream or other large body of water. The third method is adaptable to a water pressure system such as is common in cities. This latter method furnishes a 105 most efficient and rapid means of completely changing water in the tanks whenever desired, as well as scouring them.

It is well known that when water, in 110 spouts or jets, is forced or discharged by any means, upwardly from the bottom and through a body of water, a buoyancy is cre-

ated at the surface thereof and objects thereabouts are caused to float, when they would otherwise tend to sink more or less. Applying this principle, my device and its operation enables swimmers, or those learning the art, to be kept near the surface, which is very advantageous to the learners particularly. By increasing the upward force of water through the jets, a miniature storm or 10 rough water may be created to furnish pleasure to those who are practical swimmers. The device therefore combines facilities for both instruction and pleasure. In these respects it is new and useful, as well as economical and sanitary in operation. While I have shown the series of pipes 8^a below the bottom of the tank 4, these pipes may be positioned within said tank along its bottom, and provided with jets to operate in the same 15 manner, and the tank 3 omitted, without departing from the principle of my invention and constituting an equivalent thereof. This would allow the installation of my device 20 in pools now constructed, at a minimum cost. 25 In this latter arrangement of these pipes in a single tank, a spilling trough or other suitable means would be provided about the top of said tank, and the discharged water be drawn therefrom or discharged out of it in 30 the same manner as contemplated in relation to the primary tank shown, and in this respect be likewise an equivalent of the method illustrated.

I claim—

35 1. A swimming pool, wherein is combined, a tank, a secondary tank of smaller dimensions supported within the first tank free

from the bottom and walls thereof, a pipe extending from a desired source of water supply into the first tank, a series of pipes 40 extending within the first tank from the supply pipe below the secondary tank, and a series of jets extending vertically from said pipe series through the bottom of the secondary tank, the jets having tight joints at each 45 end, the whole being arranged to allow water from said source to be forced upwardly within the secondary tank to cause buoyancy near the surface of the body of water therein and allow a spill to the primary tank.

2. A swimming pool, wherein is combined, a tank, a secondary tank of smaller dimensions supported within the first tank free from the bottom and walls thereof, a pump, 55 a pipe extending from the pump within the first tank, a series of pipes extending from said supply pipe below the secondary tank, a series of jets extending vertically from said pipe series through the bottom of the 60 secondary tank, the jets having tight joints at each end, and a discharge pipe extending from an outlet in the first tank to the pump, the whole being arranged to allow water to be forced by the pump upwardly within the 65 secondary tank to cause buoyancy near the surface of the body of water therein and allow a spill to the primary tank for renewal of the water supply to the pump.

HORACE D. CARTER.
